Application July 2, 1956, Serial No. 595,543

Claims priority, application Great Britain July 19, 1955

4 Claims. (Cl. 57—77.4)

The present invention relates to improvements in or relating to the twisting and crimping of textile filaments, and in particular, but not exclusively, relates to improved twist-tubes which may be used for imparting a false twist to textile filaments passing therethrough. By the expression "textile filament" is meant any filamentary structure comprising either continuous filaments, singly or twisted together in the form of yarn, or yarns spun from staple fibres, any of which are intended for textile uses.

Twist-tubes have been in use in the textile industry for very many years, and of late they have been found particularly suitable for use in crimping thermoplastic textile filaments by a twisting, setting, and back-twisting sequence. It will be appreciated that a false-twist-tube enables such a crimping operation to be carried out in continuous fashion, instead of in separate steps, as in the case with certain other crimping processes. Heat is applied to the filaments while they are in the highly-twisted condition to set this twist, so that when the equal and opposite twist of the untwisting occurs after the filaments leave the twist tube, crimping occurs.

The principle upon which all known false-twist-tubes have operated is to cause the running filaments to acquire the rotational motion of the tube by means providing for contact with a part or parts of the inside of the tube whereby each revolution of the tube applies one revolution to the filaments. Thus the filaments may be caused to pass round a pin or pulley wheel mounted within the tube across the axis thereof or trapping means may be provided to trap them against one side of the tube. Alternatively, the bore of the tube itself may be made eccentric over some part of its length so that the filaments are caused to acquire the rotational motion of the tube by taking a short path away from the axial line. In other tubes, the filaments enter through a radial hole at one end of the tube, i.e. through a hole displaced radially from the axis of the tube.

In the process wherein a running textile filament is crimped by means of a false-twist-tube, a very high degree of twist is required; for instance, 90 turns per inch is by no means extraordinarily high, although around 75 turns per inch is satisfactory for most multifilament yarns of between 30 and 100 denier. Thus in order that the process shall be reasonably productive it has been necessary to rotate the tube at very high speeds, and speeds of the order of 30,000 r.p.m. are often used. As an example, in order that nylon continuous filament yarns should be crimped and wound up at a speed of 33 feet per minute, a rotational speed of 28,000 r.p.m. has been necessary. Such high rotational speeds of the twist-tube obviously create difficulties relating to their construction and maintenance, and it is the object of the present invention to achieve a satisfactory and, indeed, enhanced productivity of crimped yarn at considerably lower rotational speeds of the twist-tube.

This object is achieved by the present invention which comprises a twist-tube for imparting a false twist to a

2

textile filament and having its internal surface, at least at one end thereof, composed of a non-abrasive material having a high coefficient of friction with the textile filament required to be twisted thereby. The invention also 5 comprises a process whereby a false twist is imparted to a running textile filament by causing the filament to bear against, and be rotated by, the inner peripheral surface of one end, at least, of a twist-tube, and on one side of the axis thereof, the internal surface of the tube at 10 that one end at least being composed of a non-abrasive material having a high coefficient of friction with the filament. The invention also comprises the crimping of a thermoplastic textile filament by such a process, wherein the filament is heated over succeeding lengths of it- 15 self which are in the highly twisted condition to an extent sufficient to set the twist therein, the succeeding lengths of twist-set filament are then cooled before untwisting, and the untwisted filament is wound up under low tension in crimped form.

20 According to the invention, the filament is twisted by direct frictional contact with the inner peripheral surface of the tube, and thus, if the filament is held steady in the same relative position on the periphery of the tube, the ratio of the rotational speed of the filament to that of 25 the tube will depend on the ratio of the inner diameter of the tube to the diameter of the filament. It follows that, as this last ratio will be relatively large, say, of the order of 250 to 1, for a given degree of twist and a given throughput, the speed of the twist-tube can be 30 considerably reduced in comparison with a twist-tube operating according to the conventional principle in which one rotation of the tube is never capable of inserting more than one twist in the filament passing through it. Furthermore, a considerably enhanced throughput can 35 be achieved at relatively moderate rotational speeds of the twist-tube.

By "a material having a high coefficient of friction with the textile filament" is meant not only a material which, per se, has such a coefficient of friction, but also material which by reason of its surface characteristics and/or resilience has such a coefficient in practice, i.e. under operating conditions for any particular textile filament 40 as held against the material by its own tension or by other means.

As examples of materials which may be used to line the twist-tube, various sorts of rubber are suitable to a higher or lower degree, but the most eminently satisfactory material is natural rubber with carbon black filler. This material attains a polished condition after a certain amount of use, which appears to confer the necessary frictional qualities combined with resistance to wear, which are the critical features for a successful material. The filament is caused to bear against the inner periphery of the twist-tube on one side of the axis thereof by leading it towards and/or away from the tube to a guide, or guides, the path between the end of the tube and the guide or guides being at an angle (up to approximately a right angle) to the projection of the axis of the tube.

It is necessary in the first case to ensure that the correct amount of pre-tensioning has been applied to the filament. The correct angle and pre-tension for each filament can best be discovered empirically, and it should be such that some little slip occurs between the periphery and the filament, which condition, besides representing the optimum for twisting effect, is also consonant with 55 no damage to the filament. If the slip is allowed to be too great, damage may occur. Tensions such as are used in any normal false twist crimping process are satisfactory and must be such as to hold the filament firmly against the inner periphery of the tube without jumping.

70 One embodiment of the invention will now be described with reference to the accompanying drawings, in which

Figure 1 is a section through a twist tube according to the invention; and

Figure 2 is a sketch showing the use of a twist-tube according to the invention in a process for crimping a thermoplastic textile filament.

Referring particularly to Figure 1, the twist-tube comprises a fixed annular portion 1, and a driven annular portion 3 mounted on roller bearings 5, 7 therein. The driven annular portion 3 is rotated by band 9. Fitted within the driven annular portion 3 is a rubber bush 11, the inner surface of which makes direct contact with the yarn 13. The yarn is led to the tube at an angle to the axis thereof, and led away from the tube over a pulley 15, at a similar angle to the axis of the tube. Thus the yarn when suitably tensioned is kept in contact with the whole length of the inner surface of the rubber bush, and also with the two curved end portions thereof. The dimensions of a twist-tube which have been found to be satisfactory in practice, are as follows:

	Inches
Bush length	1 1/4
Bush thickness and radius of curvature of end-portions of bush	7/16

Referring now to Figure 2, a yarn 13 of thermoplastic material is withdrawn over one end of a supply package 17, and is then passed around the drum of a magnetic hysteresis tensioner 19 which imposes a constant output tension on the yarn. The yarn is then led through an infra-red heating device 21 comprising a glass tube 23 having electric resistance coils 25 wound therearound. The device is sufficiently long to ensure that the twist in the thermoplastic yarn may be set by means of the heat produced by it at the high values of yarn throughput possible in this invention. After passing through the tube, the yarn travels through the air for a sufficient time for it to cool below its plastic state, and then passes into one end of a twist-tube 27 such as that illustrated in Figure 1. The twist-tube is mounted with its axis at an angle to the vertical such that the yarn led directly through and from the heating device makes contact with one side 29 of the inner peripheral surface of the rubber bush contained within the twist-tube. The yarn is led from the twist-tube around a pulley-wheel 31, which ensures contact of the yarn with the bush at this end thereof, and therefore along the whole length of the bush. It is a question of experiment to find the most suitable angles of entry and exit of the yarn, and they will depend mainly on the denier of the yarn and the number of turns per inch of twist it is desired to insert in it. In general, however, it may be stated that angles between 45° and 90° are required, the greater angles imparting higher twist than the lesser. The angles referred to are that between the yarn entry path and the projection of the axis of the twist-tube, and that between the yarn exit path and the projection of the axis of the tube. After passing over the pulley-wheel 31 the yarn is led through the nip of a pair of forwardly rolls 33, 35 which feed the yarn forward at a slightly greater speed than that at which it is eventually wound up by the roll 37 on the package 39. Thus the yarn between the rolls 33, 35 and the wind-up package 39 is relaxed slightly. In operation, the yarn is given a high degree of false twist by means of the twist-tube, which high twist in one direction feeds back through the heating device to the tensioning device, and is set; the yarn in its twist-set condition is allowed to cool somewhat between the heating device and the twist-tube; twist in the opposite sense is imparted to the twist-set yarn directly on leaving the twist-tube; and the now crimped yarn is wound up under a low tension.

We have found that, using an apparatus according to the invention, as generally described above, in a process for crimping multifilament yarns of, for example, polyhexamethylene adipamide, once the twist tube is rotating at or above a given minimum angular velocity, the value

of turns per inch of twist inserted in the yarns is very little affected by variations in tension or speed of the yarn, or by variations in speed of the tube above the critical speed, or by the amount of wear of the material forming the inner surface of the tube. The reason for this is that, naturally, for crimping purposes, the number of turns per inch will be high, and, at these high values, the increase in torque to be imparted to the yarn to raise the number of turns per inch by, say, 5%, will require to be something of the order of 30%. Thus the settings of tube speed, and yarn tension and speed are not required to be controlled within very narrow limits, as in some other processes.

The minimum angular velocity, in revolutions per minute, of the twist tube can be ascertained from the formula:

$$V = \frac{T \times t \times 12Ry}{R_M}$$

where

V is the angular velocity in r.p.m.

T is the turns per inch of twist required

t is the speed of the textile filament in feet per minute.

Ry is the radius of the textile filament in inches.

R_M is the internal radius of the twist-tube in inches.

Furthermore, the apparatus produces a textile filament, of a given nature, of constant twist factor (i.e. turns per inch multiplied by the square root of the denier), for example, of the order of 680 or thereabouts for polyhexamethylene adipamide yarn comprising filaments of 3 denier each, so that once the apparatus is arranged to give the optimum twist to such a textile filament of a certain denier, it will be correct also for imparting the optimum twist to such filaments of any other denier.

To illustrate the variation in turns per inch of twist with denier, the following table shows the inter-relation of these two factors on multifilament yarn of polyhexamethylene adipamide, with a tube rotating at 1500 r.p.m., tension on the yarn of 25 grams, and a throughput of 170 feet per minute. The yarn entered and left the tube at the same side of the axis thereof, at an angle of 45° to the axis of the tube.

TABLE 1

Yarn Denier	210	150	100	70	60	45	30
Turns per inch	42	55	70	85	88	103	125

To illustrate the much smaller variation in turns per inch of twist with change of tension, the following table shows the inter-relation of these two factors on 60 denier multifilament yarn of polyhexamethylene adipamide, with a tube rotating at 1500 r.p.m., and with the throughput varying between 110 feet/minute and 300 feet/minute. The yarn entered and left the tube at the same side of the axis thereof at an angle of 45° to the axis of the tube.

TABLE 2

Throughput in feet/min.	110	110	110	170	170	170	170	300	300	300
Tension (grams)	15	20	25	15	20	25	30	15	20	25
Turns per inch	72	76	85	72	80	88	88	70	76	80

As examples of the use of the twist tube of the invention in processes for crimping multifilament yarn of polyhexamethylene adipamide in a continuous fashion, the following process conditions are given in Examples 1 to 11 inclusive:

Example 1

Multifilament yarn from a supply package is led through a tensioning device, such as a magnetic hysteresis type and thence over and in contact with a metal plate, electrically heated to 235° C., to the twist-tube which is rotating at 1500 r.p.m. Guides are so positioned above and below the twist-tube, whose axis of rotation is verti-

cal, that the yarn enters and leaves the tube, at one side of the axis thereof, at an angle of 45° to the axis of the tube. Under the above conditions, yarn may be processed at speeds between 20 and 60 feet/minute, and wound up on a package under low tension.

Examples 2 to 9

The process of Example 1 is carried out on 30 and 60 denier multifilament yarn but this is heated while in the highly-twisted condition by means of radiant heat within a tube, through the middle of which the yarn passes, instead of by contact with the hot metal plate. The tube is 25 cms. long and made of glass and the heat is generated by an electric resistance wire coiled around the outside of it. The temperatures expressed are those recorded by a thermocouple in equilibrium in the yarn path within the tube, and are the maximum temperatures so recorded.

Example No.	Yarn Denier	Through-put in feet/minute	Tension, grams	Temperature, °C.
2	60	205	6.5	534
3	60	205	22.0	473
4	60	300	6.5	546
5	60	300	23.0	546
6	30	200	3.5	358
7	30	200	19.0	358
8	30	300	3.5	419
9	30	300	21.0	419

Example 10

150 denier multifilament yarn was crimped by a process similar to those described for Examples 2 to 9 above, except that the heater tube was only 13 cms. long. The maximum temperature within the tube was 705° C., and the crimped yarn was produced at a speed of 200 feet/minute, with an ingoing tension of 24 grams.

Example 11

60 denier/10 filament yarn of polyhexamethylene adipamide is led from a supply package, through a magnetic hysteresis tension device which imposes an output tension of 25 grams on it, to the twist-tube rotating at 4000 r.p.m., and enters at an angle of 80° to the projection of the axis of the twist-tube. Positioned between the tension device and the twist-tube, so as to heat the yarn passing through it in its highly-twisted condition, is an infra-red heater 3 feet in length. The heater comprises a rod-like electric heating element positioned along one focus of an elliptical cross-section reflector tube surrounding it, and the yarn passes along the other focus of the ellipse. The temperature within the tube is 224° C., as measured by a thermocouple in equilibrium in the yarn path within the tube. The yarn leaves the twist-tube at an angle of 80° to the projection of the axis thereof and is wound up under low tension at a speed of 200 feet/minute.

Example 12

Polyhexamethylene adipamide monofilament of 15 denier is processed in continuous fashion by a twist-tube of the invention and in accordance with the arrangements of Example 11, except that the pre-tension imposed upon it is less than 2 grams, and the twist-tube is rotated at 4,600 r.p.m. A twist-lively filament is thus produced having some 20 turns per inch inserted, set, and removed in continuous fashion. The twist factor is low in this case owing to the different frictional nature of the surface of the monofilament, and owing to the greater torque needed to insert a given twist in such an elemental structure as a monofilament than is required for a multifilament yarn.

Example 13

50 denier multifilament yarn of the synthetic linear polyester sold as "Terylene" (registered trademark) was

75 composed of a non-abrasive material having a high co-

6
crimped in accordance with Example 11, but with the twist-tube rotating at 4,600 r.p.m.

It should be stressed that, in all the above examples, the yarn should undergo a sufficient amount of cooling after heating and before untwisting to ensure that it is not in a plastic condition such that actual deformation of it will occur during untwisting. A sufficient space between heater and twist-tube, in which the yarn passes through the ambient atmosphere, will provide the conditions for this cooling. It should also be mentioned that, if the twist-tube itself is suitably mounted so that its axis is inclined to the vertical by the requisite angle, say 45°, as shown diagrammatically in Figure 2, a convenient horizontal disposition of the several pieces of apparatus can be achieved.

Although electrical heating by contact or radiation has been described for setting, such can also be achieved by pressure steam, or by contact with heated solid particles, such as glass, in fluidized condition brought about by the passage of air therethrough.

The twist-tube of the invention has one further great advantage over those previously known, in that it is capable of imparting a false twist to several textile filaments at once. Guides may be so positioned at the entrance to and exit from the tube that a number of textile filaments may be maintained in contact with different relative positions of the inner periphery of the tube. Thus, two, three, four or more textile filaments can be processed simultaneously, and this added productivity 30 of the invention further increases its usefulness over the conventional false twist-tube and processes utilizing the same. Furthermore, by a suitable arrangement of supply and wind-up packages and guides, it is possible to impart false twist of differing senses to a plurality of 35 textile filaments, and to ply oppositely initially-twisted textile filaments together to produce balanced yarns. In this case, some textile filaments will pass through the tube in one direction, and some in the other; or one in one direction, and one in the other.

40 Suitable thermoplastic textile filaments for crimping include those of the synthetic linear polymeric amides or esters, such as nylon or "Terylene" (registered trademark), and those of cellulose acetate and triacetate. It is also possible to crimp non-thermoplastic textile filaments which have been treated with a thermosetting agent. If the textile filament to be crimped is a monofilament, it will not be practicable or necessary to impart such a high number of turns per inch of twist as for a multifilament yarn. Useful monofilaments of a twist-lively, rather than crimped, nature may be produced with a twist of from 20 to 30 turns per inch, or thereabouts, which filaments may be incorporated in fabrics in such a way as to impart stretching to those fabrics.

Finishing of articles containing yarns crimped according to this invention may be carried out in similar manner as for any known crimped yarns produced by twisting, setting and back-twisting. However, owing to the relatively far higher speed of production of the yarns according to the invention, it may be advantageous to 55 develop the bulkiness and stretchiness of the articles somewhat more slowly, and a convenient time for doing this is provided by the normal scouring treatment in liquid up to, say, 50° C. in temperature.

60 What we claim is:

1. Apparatus for imparting false twist to textile filaments comprising a rotatable member having an axial bore with outwardly flared ends extending therethrough, means guiding a textile filament to one end of said bore along a path angulated with respect to the bore axis of the order of between 45° and 90°, and means guiding the textile filament from the other end of said bore along a path angulated with respect to the bore axis of the order of between 45° and 90°, the interior surface of said bore, at least at the flared ends thereof, being 65 composed of a non-abrasive material having a high co-

efficient of friction with the textile filament, and the diameter of said bore exceeding the diameter of said filament, whereby a plurality of turns of false twist is imparted to the filament for each revolution of said rotatable member.

2. Apparatus as defined in claim 1, wherein said rotatable member is mounted on a fixed annular member by means of an anti-friction bearing.

3. Apparatus as defined in claim 1, wherein the interior surface of said bore comprises a bush composed of natural rubber with carbon black filler.

4. Apparatus for imparting false twist to textile filaments comprising a sequential arrangement of filament supply means, tensioning means, heating means, twist-tube and guide means, said twist-tube including a rotatable member having an axial bore with outwardly flared ends extending therethrough, the interior surface of said bore, at least the flared ends thereof, being composed of a non-abrasive material having a high coefficient of friction with the textile filament, and the diameter of said bore exceeding the diameter of said fila-

ment, whereby a plurality of turns of false twist is imparted to the filament for each revolution of said rotatable member, the axis of said rotatable member being angulated with respect to the filament path from said heating means to said twist-tube and the filament path from said twist-tube to said guide means.
